UNITED STATES PATENT OFFICE.

FRANK P. BARNEY, OF NORTON, MASSACHUSETTS.

IMPROVEMENT IN SEPARABLE BUTTONS OR STUDS.

Specification forming part of Letters Patent No. **222,441**, dated December 9, 1879; application filed September 13, 1879.

To all whom it may concern:

Be it known that I, FRANK P. BARNEY, of Norton, in the county of Bristol and State of Massachusetts, have invented new and useful Improvements in Separable Buttons or Studs, of which the following is a specification.

My invention relates to certain improvements in that class of buttons and studs known as "separable buttons and studs," for which Letters Patent of the United States were granted to me under date of July 8, 1879, No. 217,318, as fully described herein-after, and shown in the accompanying drawings, in which—

Figure 1 is a vertical section of the button or stud. Figs. 2 and 3 are plan views of the two sections of the button, respectively. Figs. 4 and 5 are detached views, respectively, of the patch and the locking devices with the actuating-spring; and Figs. 6, 7, and 8 are sections of the locking devices and actuating-spring, showing the method of applying the enlarging-cylinder to the push-rod of said devices. Figs. 9 and 10 are elevations of the sleeve and post, respectively.

In the above figures of drawings similar letters of reference are employed to indicate like parts wherever such may occur.

A represents the button or stud section proper, which may be of any desired shape, to which is applied the patch or re-enforce plate B, having an offset stamped out to form the anchor-shaped bearing b and bridge b', adapted to support, and upon which slides the locking-anchor and push-rod of the locking devices D. Instead of making this bearing of oval or other shape, with recesses, as described in the above-recited Letters Patent, I make it of a shape corresponding to the locking-anchor on one side of the post, with the bridge or extension, upon which the post is seated, and I leave on the opposite side of the post a sufficient amount of metal projecting above the face of the patch to form two abutments, b², on opposite sides of the path in which the push-rod reciprocates or slides, against which the free end of the actuating-spring d² abuts—that is to say, the two projecting studs b² serve as bearings for the free end of the actuating-spring d², which is here coiled around the push-rod.

C represents the post, which may be a round one, or it may be made of any other desired shape. I prefer, however, in buttons or studs of small dimensions to employ a post having the form of an ellipse or double convex, as I have found by experience that this form of post is more desirable in studs of small dimensions, taking up much less room than any other form of post relatively to its strength or capacity of resisting a given amount of strain.

The post C is provided with a recess, c, of sufficient depth to adapt it to straddle the bridge b' of the bearing and permit the free passage and working of the push-rod d of the locking-anchor d', which is thus held to its bearing by the post C, as shown in Figs. 1 and 2.

The locking devices consist of the anchor d', constructed substantially as described in above-recited Letters Patent, the push-rod d, and the actuating-spring d², which is here coiled around the push-rod. The outer end of the spring d² is secured to the push-rod by inserting it into a recess and soldering it therein, or by passing said end through a suitable perforation in the rod and riveting or bending the projecting end of said spring, as shown in Figs. 6, 7, and 8. The inner or free end of the spring d² abuts against the projecting studs b² formed on the plate B, as above related.

In studs of small dimensions, where the space for arranging the locking devices is limited, I may dispense with the abutments b² and use the post for an abutment to the spring, and for this reason I also use the form of spring above described, as the limited area of the section A in small studs prevents the use of the ordinary form of spring, as shown in my former Letters Patent, or at least that such form of spring is not as practicable as the coiled spring d², while the latter spring may be employed to advantage on any size of button or stud of this class.

In the construction of separable buttons or studs in which the sections are unlocked by a push-rod it is desirable to enlarge the outer end of said rod, which projects slightly beyond the edge of the button, for two reasons: first, to give the outer end of said rod, to which the pressure for unlocking the sections is applied,

an enlarged bearing-surface; and, secondly, to enable the manufacturer to make the push-rod and locking lever or anchor of base metal, using fine metal only for that part of the push-rod which it is designed to enlarge, and which projects beyond the edge of the button. In order to effect these two results economically and effectually without having recourse to soldering or brazing, which in articles of jewelry require the employment of skilled mechanics, I employ the following method, referring more particularly to Figs. 6, 7, and 8: I make the push-rod and its locking-anchor of any suitable hard base metal, and form upon the outer end which is to be enlarged a series of teeth or serrations, as shown at D'. Then I take a hollow cylinder of fine metal, open at both ends, and slip it onto the end of the push-rod, and by means of a suitable tool I press or swage the cylinder D² onto the rod, so as to force the softer metal of the cylinder into the interstices between the teeth and serrations D' on the push-rod, as shown by Figs. 7 and 8, by means of which said cylinder is firmly attached to the push-rod end and made to practically form an integral part thereof, the parts being thus more intimately connected together than by soldering, and at considerable less expense and labor.

Under some circumstances, especially in the high-priced class of this kind of jewelry, it is also desirable that the end of the push-rod should be covered from view by the finer metal, in which case I form the end of the push-rod tapering or attenuated outwardly, and the opening in the cylinder D² of a corresponding taper, so as to leave an increased thickness of metal at the outer end, and when swaged onto the end of the push-rod the cylinder will be slightly elongated, and its outer end made to overlap or close over the end of the push-rod, thus hiding it from view.

E represents the other section of the button or stud, carrying a double convex or elliptical sleeve, F, adapted to fit and slide over the double convex post C.

The sleeve has recesses f on opposite sides, with which engage the side arms of (if I may so express it) the flukes of the anchor d', and a recess, f', of sufficient depth to straddle the push-rod d and the bridge b' of the bearing b. When there are no abutments employed for the coiled spring the width of the recess f' and

its depth are such as to adapt the sleeve to straddle the spring and permit it to abut against the post C.

Having now described my invention, what I claim, and desire to secure by Letters Patent, is—

1. In a separable button in which the two sections are locked together by a locking-lever under the action of a spring, the combination, with the section A, of the plate B, having the anchor-shaped offset b and projecting abutments b², to form a bearing for the locking devices, a seat for the post, and an abutment for the actuating-spring, as described.

2. In a separable button, the combination, with the section A, its plate B, having the bearings b b' and the abutments b², and the post C, of the locking-anchor D and spring d², coiled around the push-rod d of said anchor, all arranged and operating substantially as described, for the purpose specified.

3. In a separable button, the combination, with the section A, its plate B, having the bearings b b' and the abutments b², the post C, the anchor D, and the spring d², coiled around the push-rod of said anchor, and having its outer end rigidly connected therewith and its inner or free end made to bear upon said abutments b² of the section E and its sleeve F, all arranged and operating substantially as described, for the purpose specified.

4. In a separable button or stud, the combination, with the push-rod of the locking devices, having its outer end serrated or provided with teeth, of a hollow cylinder surrounding said serrated end, as and for the purpose specified.

5. In a separable button or stud, the combination, with the push-rod of the locking devices, having its outer end made tapering and provided with serrations or teeth, of a cylinder having an axial opening corresponding with the tapering end of said push-rod and surrounding said end, as and for the purpose specified.

In witness that I claim the foregoing I have hereunto set my hand this 8th day of September, 1879.

FRANK P. BARNEY.
